H. M. COOPER, OF LINDLEY, MISSOURI.

Letters Patent No. 70,964, dated November 19, 1867.

IMPROVEMENT IN LOOMS.

The Schedule referred to in these Letters Patent and making part of the same.

TO ALL WHOM IT MAY CONCERN:

Be it known that I, H. M. COOPER, of Lindley, in the county of Grundy, and State of Missouri, have invented a new and useful Improvement in Hand-Looms; and I do hereby declare that the following is a full, clear, and exact description thereof, which will enable others skilled in the art to make and use the same, reference being had to the accompanying drawings, forming part of this specification, in which—

Figure 1 is a vertical longitudinal section, taken in the line $\alpha\alpha$, fig. 3.

Figure 2, a side view.

Figure 3 is a plan or top view of my improved loom.

Similar letters of reference indicate corresponding parts.

This invention relates to improvements in the construction of hand-looms, and consists in an arrangement of mechanism in connection with the lay or batten, by the motion of which, back and forth, all the operations of the loom are performed; the whole structure being simple, easily regulated, and kept in order, while the working of the loom is positive and effective in every part for weaving fine or coarse cloths in the best manner, as hereinafter more particularly described.

A is the framing, B the breast-beam, C the lay or batten, D the cloth, and E the warp-roll; F the harness-frame, and G the treadles, of which there are two sets, corresponding to each other, placed in each side of the frame, and connected with the harness-frames. The treadle-cam shaft H is operated by means of ratchet-wheels $\alpha\alpha$, on each end, actuated by ratchets $b b$, attached to levers $d d$, fitted loosely on the ends of the shaft H, which levers are connected by the rods $e e$ with the lay C, so that with each back stroke of the lay the cam-shaft is turned partly around, and raises corresponding treadles in each of the sets G G, by means of cams or tappets, as usual. Thus the shedding movement is given to the harness by the motion of the lay itself by two corresponding treadles at a time, on opposite sides of the frames or treadles, which are thus lifted steadily and evenly. For giving the feed or take-up motion to the cloth-beam or roll D, a train of gear-wheels, $g^1 g^2$, receive intermittent motion corresponding with the weaving of the cloth when the weft is struck up, by means of a ratchet-wheel, h , actuated by a pawl, k , attached to a lever, m , connected by the rod n with the lay-sword C'. The speed can be adjusted by shortening or lengthening the lever m . For driving the shuttle back and forth, an angular block or hand, p , is pivoted in a recess at the middle of the under side of the lay, which hand is connected with the shuttle-drivers $o o$ by cords $q q$. And attached to the inside of the breast-beam B, so that they can rise and fall at their outer ends, are two levers, $r r$, which pass under the hand p on each side between guides, and then bend downward from the lay to the treadle-cam shaft H, over the cams $s s$, and are raised by the cams alternately with each movement of the lay. The levers $r r$ are thus raised alternately and brought into contact with the hand p in such a manner that the hand shall be turned to the right and left alternately, and thus operate the shuttle-drivers either on the right or left at every forward stroke of the lay. The shuttle is not operated on unless the harness changes, and therefore there can be no balks in the cloth. The shuttle-boxes $t t$ are attached to the frame of the lay by hinges w , fig. 2, to permit their being folded down close by the side of it out of the way when the loom is not in operation. A rod or bar, v , is fixed in the swords of the lay, running across between them, in such a position that when the lay is thrown forward the rod shall strike the ends of the treadles, and ride upon those which are down, in order to bring and hold the warp-threads down evenly on the lay, and thus enable the shuttle to pass clear and smoothly over them. And when the ends of the treadles are thus pressed down by the rod v , they bear upon a cross spring-bar, w , to produce the necessary tension on the warp for keeping it even on the lay without excessive strain.

It will be evident that by this arrangement of the various working parts of the loom, in connection with the lay as described, they will all perform their several offices by the motion of the lay back and forth in weaving, so that the operation shall be easy, regular, and certain.

Having thus described my invention, what I claim as new, and desire to secure by Letters Patent, is—

1. The combination of the lay C, the treadle-cam shaft H, the treadles G, the cloth-beam D, the shuttle-driving hand p , the levers $r r$, the cams $s s$, the spring-bar w , and the cross-bar v , connected, arranged, and operating as and for the purposes herein described.

2. The combination and arrangement of the lever m , pivoted near its lower end to the frame of the loom,

and provided at its upper end with the screw-thread by means of which the hinged pawl *k* is raised or lowered, with the connecting-rod *n*, sword *C'*, cloth-beam *D*, gear-wheels *g* *g*¹ *g*², and ratchet-wheel *h*, as herein described for the purpose specified.

3. The arrangement of the pivoted hand *p*, the levers *r* *r*, the cams *s* *s*, the spring-bar *w*, and the cross-bar *v*, combined with the lay *C* and the shuttle-drivers *o* *o*, substantially as and for the purposes described.

4. Connecting the shuttle-boxes *t* *t* with the lay by hinges as and for the purpose set forth.

The above specification of my invention signed by me this 11th day of March, 1867.

H. M. COOPER.
